(57) **CLAIM**

The ornamental design for a wearable computer, as shown and described.

DESCRIPTION

FIG. 1 is a front elevational view of a wearable computer showing my new design;

FIG. 2 is a top plan view thereof;

FIG. 3 is a right side elevational view thereof;

FIG. 4 is a rear elevational view thereof; and,

FIG. 5 is a front and top perspective view thereof.

The broken lines shown in the drawings illustrate portions of the wearable computer and form no part of the claimed design.

The dash-dot line represents the boundary of the claimed design.
